CLAIM

The ornamental design for a portion of a flow generator, as shown and described.

DESCRIPTION

FIG. 1 is a front perspective view of a portion of a flow generator according to my/our design; and,

FIG. 2 is a front view thereof.

Where included, broken lines showing environment or structure are for illustrative purposes only and form no part of the claimed design.

UNITED STATES PATENT AND TRADEMARK OFFICE
CERTIFICATE OF CORRECTION

PATENT NO. : Des. 579,543 S
APPLICATION NO. : 29/287121
DATED : October 28, 2008
INVENTOR(S) : Lithgow

Page 1 of 1

It is certified that error appears in the above-identified patent and that said Letters Patent is hereby corrected as shown below:

Title Page, Item (12) should read -- Lithgow --.

Please correct the following error on the front page, item (75) of the above-identified design patent:

Delete "John Michael Snow, Cremorne (AU);

Dan Kao, Chatswood (AU);

Ian Malcolm Smith, Westleigh (AU);

William Bonilla, Blacktown (AU)".

Signed and Sealed this

First Day of September, 2009
